(57) **CLAIM**

The ornamental design for a wall mounted bracket for storing hitch mounted bike racks and accessories, as shown and described.

DESCRIPTION

FIG. 1 is a perspective view of a wall mounted bracket showing my new design.

FIG. 2 is a side elevation view of one side thereof, the opposite side being a mirror image.

FIG. 3 is a front view thereof.

FIG. 4 is a top view thereof, the bottom view being a mirror image; and,

FIG. 5 is a back view thereof.

The broken lines showing openings are for the purposes of illustrating environment and form no part of the claimed design.
